[57] CLAIM

The ornamental design for a deer torso protective cover, as shown and described.

DESCRIPTION

FIG. 1 shows a top view of the present invention;
FIG. 2 shows a bottom view of the present invention;
and,

FIG. 3 shows a side view of the present invention with
the environment of intended use shown in phantom.
The material is of conventional thickness. The dashed
lines in FIGS. 1-3 are to show conventional stitching.
The broken lines in FIG. 3 are for purposes of illustration
only and form no part of the claimed design.

FIG. 1

FIG. 2

FIG. 3
